CLAIM

The ornamental design for a shoe outsole, as shown and described.

DESCRIPTION

FIG. 1 is a rear perspective view of a shoe outsole showing our new design;

FIG. 2 is a bottom view thereof; and,

FIG. 3 is a front perspective view thereof.

The broken lines immediately adjacent to the shaded area represent unclaimed boundaries of the design. The fourteen unshaded regions, demarcated by broken lines, represent unclaimed portions of the shoe outsole and form no part of the claimed design. The broken lines showing the remainder of the shoe are for environmental purposes only and form no part of the claimed design.
